STAMPING MACHINE

Lewis A. Kingsley, Los Angeles, Calif.

Application April 4, 1932, Serial No. 602,996

6 Claims. (Cl. 101—9)

My invention relates to a device for stamping letters or characters in metallic foil, such as gold leaf, on articles, and is of especial utility in stamping names on fountain pens or other articles or sheet material, such as cloth, leather, fabrikoid, etc.

It is an object of my invention to provide a device of this character of simple construction which may be operated by unskilled operators, 10 but which is so constructed that perfect results may always be obtained therefrom due to the maintained alignment of the operating parts of the device.

It is an object of my invention to provide a 15 device having a vertically movable stamping head adapted to receive a type holder and having means for heating the type, having simple means for holding articles in proper position to be stamped. One of the important uses of the device is in stamping names on fountain pens, and for this purpose my invention provides a removable fountain pen holder which is adapted to be received on the base of the device in a position of alignment relative to type held in the stamping 20 head, but which may be removed so that the fountain pen, pencil, or article of similar shape held in the holder may be inspected after a stamping impression has been made, and may be restamped or impressed by placing the holder again in position on the base of the device and lowering the heated type. In devices of this character at present employed, a grooved channel is provided in which the article, such as a fountain pen or pencil, to be stamped is placed. 25 To inspect the imprint which has been made is difficult unless the stamped article is removed from the device so that it can be held up to the light, and replacement of the stamped article in its original position is very difficult, if not impossible; therefore, the making of a second impression over an original impression is very difficult 30 in the present type of equipment.

In the use of my device, the article to be stamped is clamped in the removed self-aligning holder, and after an impression has been made the holder may be lifted from the stamping device and the impression inspected. If the impression is not complete, the replacing of the holder in the stamping device will automatically 40 bring the impression into a position of alignment with the type so that the type will engage the characters or letters of the impression when the stamping head is again lowered.

It is a further object of my invention to provide 45 a device of the above character having a stamp-

ing head of simple form equipped with simple means for maintaining it continuously in working alignment so that the type received in the stamping head will always be lowered into engagement with the article to be stamped, in a 5 position of practically perfect alignment. This alignment is of great importance in the stamping of cylindrical objects, such as fountain pens and pencils, for in order to obtain a good imprint quickly and easily, the line of type must be aligned 10 with a plane intersecting the axis of the cylindrical object to be stamped.

A further object of the invention is to provide in a device of the above character a stamping head equipped with a reversible type holder so 15 that the type may be placed so as to read forwardly or rearwardly, and may be reversed from one position to the other by merely reversing the type holder without the necessity of changing the type in the type holder. 20

A further object of the invention is to provide a device of this character having a removable table adapted to be placed on the base in level position and also having a simple means for holding an article, such as a pocketbook, on the removable table preparatory to the stamping operation. 25

Further objects and advantages of the invention will be brought out in the following part of the specification. 30

Referring to the drawings which are for illustrative purposes only,

Fig. 1 is a partly sectioned side elevation of a stamping device embodying my invention. 35

Fig. 2 is a partly sectioned front elevation taken as indicated by the arrow 2 of Fig. 1.

Fig. 3 is a cross-section on a plane represented by the line 3—3 of Fig. 1, the holder being removed from the base in this view.

Fig. 4 is a perspective view showing the removable holder removed from its position of alignment in the machine for the purpose of inspecting the stamped article. 40

Fig. 5 is a perspective view showing the simple form of type holder I employ. 45

Fig. 6 is a view taken from the position indicated by the line 6—6 of Fig. 2, showing the type holder in one position of use in the stamping head.

Fig. 7 is a view similar to Fig. 6, showing the type holder in reversed position. 50

Fig. 8 is a view similar to Fig. 1, showing the manner in which flat objects, such as fabric and leather goods are stamped, by use of the removable table and holding means of the device. 55

- As shown in Fig. 1, my invention provides a base 11 preferably of rectangular form, having a gooseneck support or bracket 12 extending upwardly from the rear end thereof and bent forwardly so as to reach a position above the forward end 13 of the base 11. Supported in the forward end 14 of the bracket 12 is a stamping head 15 having a central bar or shaft 16 which extends upwardly through a vertical opening 17 in the front end 14, and has a horizontal plate 18 at its upper end projecting rearwardly over a compression spring 20 adapted to normally hold the stamping head 15 in raised position. The lower end of the stamping head 15 comprises a body 21 of rectangular prismatical form placed to extend laterally with respect to the rectangular base 11 above which it operates. This body 21 has a groove or channel 22 in the lower portion thereof adapted to receive a type holder 23.
- 20 In a downwardly extending front wall 24 defining the groove 22, a clamping screw 25 is mounted, this clamping screw having a head 26 of low heat conductivity. On the lower end of a downwardly extending rearward wall 27 defining the groove 22, a plate 28 is mounted in such position that the forward edge 29 thereof will project beyond the inner face of the wall 27 and thus provide a shoulder which will prevent the type holder 23 from dropping from the channel 22.
- 30 The rearward portion 31 of the plate 28 is bent upwardly in spaced relation to the outer face of the wall 27 to provide a space or pocket 32 in which an electrical heating element 33 of flat form may be placed in the manner best shown in Fig. 1.
- 35 This heating element 33 consists of a resistance wire wound on a flat body of insulating material, such as mica, the heating coil thus formed being covered by sheet insulating material, thereby providing a heating element of flat or wafer form which is held against the body 21. From the heating element 33 a flexible duplex cable 35 is carried to a switch 36 mounted on the rearward portion of the bracket 12 in the manner shown in Fig. 1, and from the switch 36 electric conductor means 37 is carried to a suitable electrical outlet.
- 40 As shown in Fig. 5, the type holder includes a pair of plate members 40 and 41 adapted to be moved longitudinally by means of a screw 42 which passes through a flange 43 formed at one end of the member 40 and engages the flange 44 on the end of the member 41. A space 39 of proper width to receive a line of type 45 is formed between the members 40 and 41, and the type 45 is clamped in this space by pressure on the ends of the line of type accomplished by use of the screw 42 which is also equipped with a head 46 of low heat conductive material. The end portion 47 of the flange 43 projects beyond the outer face of the member 41 so as to provide a stop which engages either end of the body 21 of the head 15 when the type holder 23 is slid into the channel 22 from one end or the other thereof.
- 45 In the use of the holder 23, it is preferable to set up the line of type 45 and if such line of type does not fill the type space 39, it is preferable to fill in the ends thereof with quads 48, as shown in Fig. 5, in a manner to position the type centrally with respect to the holder. As shown in Figs. 1, 2, and 6, the holder, when inserted in the channel 22, is, except for its ends, in heat conducting relationship with the walls of the channel, and the holder may be inserted 50 in the channel 22 of the body 21 from the left- 55 ward end thereof to bring the stop portion 47 into engagement with the leftward end of the body 21, after which the screw 25 may be tightened to prevent movement of the holder 23 in the channel 22, the type then reading in forward direction and being in forward position; or the holder may be inserted in the channel 22 from the rightward end thereof, as shown in Fig. 7, in which event the stop portion 47 will engage the rightward end of the body 21, the type then reading in reverse direction and being in reverse position but being substantially centralized relative to the stamping head 15. This stamping head and cooperating type holding means, besides being simple and economical in construction, is very easy to operate. The body 21 which is heated by the heating element 33 need not be touched by the hands of the operator, and the type holder 23 may be readily removed by engaging the head 46 of the screw 42 and pulling the holder 23 from the channel 22 without danger of burning the hands of the operator, and without the necessity of swinging the body 21. It will be noted that in this simple construction, the stamping head has no swingably mounted parts which may wear and become disaligned, but is at all times in alignment with a laterally directed vertical plane indicated by the lines A—A of Figs. 1 and 3.
- 55 A feature of my invention concerns the simple means whereby the stamping head 15 is maintained permanently in alignment with the plane A—A. Formed in laterally extending positions on the front end 14 of the bracket 12 are lugs 50 having vertical openings 51 through which 60 guide pins or bars 52 are projected upwardly from the end portions of the body 21. The members 52 sliding vertically in the openings 51 hold the body 21 in alignment with the plane A—A.
- 60 As shown in Figs. 1, 2, 3, and 8, the base 11 has a pair of upwardly projecting bosses or pads 55 near the forward end thereof and centralized with respect to the plane A—A. The upper faces 56 of these pads lie in a horizontal plane, and formed centrally in the pads 55 and on the plane 65 A—A are openings 57 forming part of a guide or aligning means for a removable holder 58, shown in Figs. 1, 2, and 4. This holder 58 consists of a metal body 59 having a V-channel 60 in the upper face thereof so aligned with respect 65 to dowel pins 61 which project downwardly from the body 59 that when the dowel pins 61 are inserted in the openings 57, the channel 60 will be aligned with the plane A—A and will hold a cylindrical object, such as a fountain pen 63, 70 65 which is also aligned with the plane A—A. The removable holder 58 has a forwardly projecting portion 64 from which a stud 65 projects upwardly, this stud extending through an opening 60 in a clamping plate 66 and having a toggle lever 67 on its upper end adapted to force the plate 66 downwardly, so that fingers or curved portions 68 formed at the ends of the plate 66 will bear downwardly on the cylindrical object, such as the fountain pen 63, and hold it immovably in the channel 60. The clamping plate 66 has the forward end 70 thereof bent downwardly so as to provide a fulcrum point on which the plate 66 may swing when the central portion thereof is forced downwardly by swinging the lever 67 from vertical to horizontal position. The clamping plate 66 is held in alignment on the body 59 by means of guide pins 72 which project upwardly from the body 59 through openings 73 in the plate 66.

The stamping of an object, such as the pen 63, held in the holder 58 as shown in Figs. 1 and 2, is accomplished in the following manner. By forcing rearwardly and downwardly on a handle 15 pivotally mounted on a shaft 16 held in the upper end of the forward portion 14 of the bracket 12, a cam member 11 is rotated downwardly in engagement with the plate 18 at the upper end of the vertical bar 16 of the stamping head 15, thereby causing the stamping head 15 to move downwardly and carry the type 45 forcibly into engagement with the upper portion of the pen 63. Prior to the lowering of the stamping head, heat is produced to heat the type 45 to a desired temperature, by use of the electrical heating element 33, and prior to the lowering of the type 45 into engagement with the pen 63, a sheet of metal is placed over the portion of the pen 63 to be stamped, or such foil is applied directly to the faces of the type 45. After making an imprint, the holder 58 may be lifted bodily from its aligned position on the base 11, as shown in Figs. 1 and 2, and the lettering 78, shown in Fig. 4, may be inspected. Should one or more of the letters, as indicated at 80, be indistinct, the holder 58 may be replaced in the stamping machine, and the stamping head 15 may be again lowered to re-impress the type in the same position as the original impression or printing 78.

As shown in Figs. 3 and 8, the base 11 has a third upwardly projecting boss or pad 81 placed near the forward portion of the upright part of the bracket 12. A hole 82 projecting vertically through the pad 81 is adapted to receive a dowel pin 83 which extends downwardly from a table or plate 84 adapted to receive flat articles, to be stamped. The plate 84 has dowel pins near the forward end thereof, such as the dowel pin 85, of Fig. 8, which projects into the openings 57 when the plate 84 is in operative position on the base 11 of the stamping device. A boss 86 on the rearward portion of the base 11 supports a screw 87 to which a curved leaf spring 90 is secured so as to swing across the upper face of the plate 84 and to bear down on any article, such as a wallet or pocketbook 91, placed on the table 84, whereby to hold the article 91 in a desired position for stamping.

Although I have herein shown and described my invention in simple and practical form, it is recognized that certain parts or elements thereof are representative of other parts, elements, or mechanisms which may be used in substantially the same manner to accomplish substantially the same results; therefore, it is to be understood that the invention is not to be limited to the details disclosed herein, but is to be accorded the full scope of the following claims.

I claim as my invention:

1. A removable type holder for stamping a device, including: a pair of longitudinally slidable members forming a type receiving opening therebetween, there being a shoulder on one of said members forming one end of said type receiving opening and a shoulder on the other of said members forming the opposite end of said opening, one of said members having a slot therein; an adjusting element threaded through one of said members and engaging the other of said mem-

bers, said element being adapted by rotation for changing the length of said opening; and a locking element extending through said slot in one of said members and associated with the other of said members for releasably locking said members 5 against relative transverse movement.

2. A removable type holder in a stamping device, including: a pair of longitudinally slidable members forming the sides of a type receiving opening therebetween, there being a shoulder on each of said members, said shoulders forming the ends of said type receiving opening; and an adjusting element threaded through one of said members for engaging the other of said members and adapted by its rotation to change the length 15 of said type receiving opening.

3. A type holder adapted to be slidably received in a channel of a stamping head, including: a pair of longitudinally slidable members forming the sides of a type receiving opening therebetween, there being a shoulder on each of said members forming the ends of said type receiving opening, and a second shoulder on one of said members projecting beyond the other of said 25 members for limiting the movement of said members in the channel by engagement with the stamping head; and an adjusting element threaded through said second shoulder for engaging the other of said members and adapted by its 30 rotation to change the length of said type receiving opening.

4. In a device for stamping an article, the combination of: a stamping head having a stamping movement relative to the article and having a channel in the lower part thereof; a pair of longitudinally slidable members forming the sides of a type receiving opening therebetween, said members being adapted for slidable reception in said channel; a shoulder on each of said members, said shoulders forming the ends of said type receiving opening; and an adjusting element threaded through one of said members for engaging the other of said members, said adjusting element upon the application of axially directed 40 force inducing movement of said members relative to said stamping head and upon the application of rotational force inducing relative movement of said longitudinally slidable members to change the length of said type receiving opening. 45

5. A stamping device including: a stamping head having a channel therein; a type holder slidably received in said channel and having portions engaging the periphery of said channel with either end of said holder adjacent either end 55 of said channel; and heating means associated with said head for heating said type holder.

6. In a stamping device, the combination of: a stamping head having a channel therein: a type holder slidably received in said channel; a plate member on said stamping head projecting over a portion of said channel and engaging said type holder whereby said type holder is held in contact with the walls of said channel; type in said type holder having its face projecting beyond 60 said stamping head, said type holder and said plate; and heating means on said stamping head 65 for heating said type holder and said type.

LEWIS A. KINGSLEY.
